[57] CLAIM

The ornamental design for a vehicle luggage carrier, as shown and described.

DESCRIPTION

FIG. 1 is a front elevational view of the luggage carrier showing our new design;

FIG. 2 is a top plan view thereof;

FIG. 3 is a rear elevational view thereof;

FIG. 4 is an enlarged, end elevational view thereof, the opposite end being a mirror image of that shown; and

FIG. 5 is a bottom plan view thereof.
